UNITED STATES PATENT OFFICE.

MAHLON WELLS, OF HAUGHVILLE, INDIANA.

CAR-COUPING.

SPECIFICATION forming part of Letters Patent No. 554,610, dated February 11, 1896.

Application filed July 8, 1895. Serial No. 555,189. (No model.)

To all whom it may concern:

Be it known that I, MAHLON WELLS, a citizen of the United States, residing at Haughville, in the county of Marion and State of Indiana, have invented certain new and useful Improvements in Car-Couplings; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to a device for connecting railroad-cars together in a train; and it consists of a new and novel coupling to be attached to an end of a car in the usual manner, and by which the car may be automatically coupled to another car having a like coupler or an ordinary link-and-pin draw-bar, and will be more fully described hereinafter.

My object is to provide a cheap and reliable automatic coupling that may be used in connection with any other form of coupling as well as with those like itself, and with this end in view I have constructed a coupling that is cheaply constructed, of few parts, economical and durable in use.

Referring to the drawings, Figure 1 represents a longitudinal side view; Fig. 2, an end view; Fig. 3, a longitudinal view, half-plan of top and half-sectional through center; and Fig. 4 is a longitudinal vertical sectional view through center.

The draw-head D is a casting of common iron, steel, or malleable iron, having an open mouth d for the reception of the coupling-bar C. Suitable openings are cored in the head, into which the coupling-hooks A A' are secured; also holes into which the bolts e and h are inserted. A suitable hole is also cored into the bottom of head for the reception of the uncoupling-pin n, and a hole l in bottom and a like hole k in upper lip B is provided to receive a coupling-pin when an ordinary coupling-link is used in connection with link-and-pin coupling. The upper lip or top B is a casting of iron or steel and is secured in its place to form the top wall of draw-head by the hinge-bolt h passing through a hole near its rear end, while its forward end

rests upon shoulders in the mouth to keep it in a horizontal position, yet permitting the forward end to be raised when desired. A leaf 55 or plate spring g is attached by a screw-bolt o at one of its ends to the rear top part of the draw-head D, while its other end presses upon the top of lip B, holding it normally in place, but yielding sufficiently to allow the 60 lip to be raised.

The coupling-hooks A A' are secured in the side recesses of the head D by bolts e passing through holes near and back of the center of each hook-bar, respectively. At the rear end 65 of the hook-bars a coiled spring f is interposed between them, pressing the ends apart so that, the hook-bars being pivoted near their center, their opposite ends consequently are normally held toward each other. Shoulders 70 j are provided at forward end of recesses, against which the end of hook-bars come in contact when under the strain of pulling, instead of straining the pivot-bolts e, thus obviating the danger of bending the bolts. 75

The coupling-bar has at each end an arrow-head forming on the sides the lugs b b', and also a hole i to receive a coupling-pin when it is used in connection with a link-and-pin draw-head. At each side of the forward end 80 of draw-head suitable ears r are attached by means of screw-bolts, and to these the uncoupling-levers p are attached by means of the loose pins S. The upper ends of levers p are connected by rods t, which extend to each 85 side of a car, respectively, so that a car may be uncoupled from another from either side of the track without requiring a man to go between the cars. The uncoupling-pin n having the yoke m rests upon the lower ends of 90 the two levers p and is in a normal position when down, as shown in Figs. 1 and 2.

In practical operation the draw-head D, having the usual shank at its rear, is secured to one end of a car in the usual manner. The 95 coupling-bar C enters the mouth d. The point c comes in contact with the beveled points of hooks a a' and forces them apart, as shown at a', Fig. 3, and when the point b has passed the point a the hooks close together and engage the lugs b b', performing the act of coupling, the end c' being held in the draw-head of an adjacent car. To uncouple the two cars, one of the rods t is drawn 100

toward the side of car, which action forces upward the pin *n* against the under side of bar *C*, which in turn raises the upper movable lip *B*, permitting the lugs on side of bar *C* to rise above the hooks *a a'*, when the bar *C* may be withdrawn by the opposing car or by hand, if desired, thus completing the act of uncoupling.

Having described my invention, what I claim as being new and novel, and desire to secure by Letters Patent, is—

1. In a car-coupling the combination of the coupling-hooks *A, A'* with the pivot-pins *e, e* and coiled spring *f*; the movable lip or top *B* with pivot-pin *h*; the spring *g*; the lugs *r, r*; the levers *p, p* of bell-crank form having pivotal pins *S, S*; the uncoupling-pin *n* having the yoke *m*, and the coupling-bar *C* having pin-holes *i i*, substantially as and for the purpose shown and described.
2. The combination, in a car-coupling, of the coupling-hooks *A, A*, having the shoul-

der at forward end bearing at *j*; the hooks *a a'*, the shoulder *j* in the side opening of draw-head *D*; the arrow-head coupling-bar *C* having the pin-hole *i, i*, the hinged top *B* of draw-head; the spring *g*; the uncoupling-pin *n* having the yoke *m*; the levers *p, p*, and the lugs *r r*, substantially as and for the purpose shown and described.

3. In a car-coupling, having coupling-hooks, the combination of the shoulder *j* in recess of head; the shoulder at end of hook-bar conforming to shoulder *j* in head; the hinged top *B* of draw-head; the spring *g*; the uncoupling-pin *n* having the yoke *m*, and the levers *p, p* attached to lugs *r, r*, substantially as and for the purpose shown and described.

In testimony whereof I affix my signature in presence of two witnesses.

MAHON WELLS.
